DESIGN FOR A SIGNAL AND CODE DIAL

Arnold Opler, Riverside, Ill.

Application February 6, 1935, Serial No. 55,278

Term of patent 7 years

To all whom it may concern:

Be it known that I, Arnold Opler, a citizen of the United States, residing at Riverside, in the county of Cook, in the State of Illinois, have invented a new, original, and ornamental Design for a Signal and Code Dial, of which the following is a specification, reference being had to the accompanying drawing, forming a part thereof, in which:

Fig. 1 is a plan view of a signal and code dial, showing my design; and

Fig. 2 is a vertical sectional view taken as indicated at line 2 of Fig. 1.

I claim:

The ornamental design for a signal and code dial, substantially as shown.

ARNOLD OPLER.
